GEORGE M. WILSON, OF SCHENECTADY, NEW YORK

BOILER MUD RING STRUCTURE

Application filed December 23, 1931. Serial No. 582,762.

This invention relates to steam boilers and particularly to the bottom ring commonly called the mud ring which holds the inner and outer fire-box sheets in spaced relation. 5 The object of the present invention is to provide an improved boiler mud ring structure, which will be characterized by strength and durability making for increased longevity of service, relative lightness in weight, and 10 being economical to construct, while at the same time being of sufficient flexibility in combination with its strength to meet all the requirements of service.

Mud rings of rectangular cross section to 15 which the fire-box sheets are attached by rivets passed through the sheets and the ring, have been employed in common practice, and in recent constructions the bottom edges of the sheets have been welded to the rings to 20 increase the tightness of the joints. Prolonged service, however, frequently causes the rivets of such structures to loosen and cause cracks to form between the rivet holes in the mud ring and the sheets. The necessary re- 25 pairs, because of these defects, are costly in both time and labor. Such loosening and cracking especially when near the corners of the structure, if not properly repaired, results in erosion of the scarfed edges of the sheets 30 to the extent of requiring their replacement sooner than would otherwise be necessary.

The present invention provides a structure wherein the rivets formerly employed for the attachment of the sheets to the ring 35 are entirely eliminated together with the objectionable results caused thereby. This structure comprises a ring of considerably reduced weight, which ring is of ample strength to withstand all of the stresses im- 40 posed upon it by reason of the boiler pressure on the inside and by reason of the shocks and vibrations of the frame structure of the locomotive, which are commonly met with in everyday practice. Further, the structure is 45 characterized by a certain flexibility enabling it to adjust itself to irregular expanding and contracting movements of the boiler caused by differences and changes in temperature.

Referring to the drawing, wherein there is 50 illustrated a specific embodiment of the pres-

ent invention, and wherein like reference characters on the several figures indicate like parts, Fig. 1 is a horizontal sectional view of a part of the mud ring structure of the instant invention, taken on the line I—I of Fig. 2; Fig. 2 is a fragmentary section taken on the line II—II of Fig. 1; Fig. 3 is an end view in elevation of a part of the structure illustrated in Fig. 1; Fig. 4 is a section on an enlarged scale of the mud ring, taken on the line IV—IV of Fig. 3; and Fig. 5 is a section on an enlarged scale of the mud ring, taken on the line V—V of Fig. 1 showing the wash-out plug in position.

Referring in detail to the drawing the structure embodying the instant invention comprises a closed rectangular mud ring 1, having a bottom portion 2, and two upwardly extending outer and inner side walls, 3 and 4, respectively. The ring is thus of hollow, upstanding U-shaped construction. The upwardly extending outer and inner side walls 3 and 4, are of reduced thickness at their upper portions 5 and 6 providing ledges 7 and 8, and a plurality of threaded bolt holes 9 are formed in the upper portions 5 and 6 of the walls, around the entire ring, the holes of the outer wall being oppositely disposed with relation to or aligned with the holes of the inner wall. The upper edges of the walls 7 and 8 are bevelled at 5a and 6a, to avoid the lodgement of sediment thereon, when the boiler is in operation, with the boiler sheets assembled with the ring as hereinafter described.

Outer fire-box sheets 10 extend upwardly from the mud ring with their lower ends adjacent the outer sides of the upper portion 5 of the mud ring wall 3, and with their edges adjacent the ledge 7, so that the outer surfaces of the mud ring and the outer fire-box sheets are flush with each other. Similarly, inner fire-box sheets 11 extend upwardly from the mud ring with their lower ends adjacent the outer surface of the upper portion 6 and their lower edges adjacent the ledge 8 of the mud ring wall 4, the outer surfaces of the inner fire-box sheet 11 being flush with the outer surface of the mud ring wall 4. Bolt holes 12 are formed in the fire-box sheets opposite to or in alignment with the

holes 9 in the mud ring and staybolts 13 are passed through the holes of the sheets and of the mud ring walls, and secure the sheets to the ring. The staybolts 13 are threaded and engage the threaded bolt holes 9, and the extremities of the staybolts are headed over at the outer sides of the sheets. The lower edges of the sheets, adjacent the ledges 7 and 8 are welded to the mud ring as indicated at 14, the weld deposit filling the space therebetween and providing additional securing means between the sheets and the ring, and making for increased strength and tightness of the jointure. The fire-box sheets are made in sections in the usual manner and overlap at their meeting edges, and are riveted together in the usual manner at such edges, as indicated at 15. The bottom portion of these connecting edges, however, are cut away at 16 the portions where they would otherwise overlap, as indicated at 16, so as to evenly meet and present a continuous even surface at the portion of the sheets connected with the mud ring. Rivets 17 are provided at the corner portions of the sheet securing said portions to the mud ring to assist the corner staybolts, so as to strengthen the same, and the adjacent edges of the sheets at the cut away portions are welded as indicated at 18, to insure a sturdy and steam-tight connection. By this means, the jointure of the section of sheet of one side of the ring with the section of sheet of an adjacent side is accomplished.

35 The mud ring is provided with wash-out openings 19 at its corners. The openings slant downwardly and outwardly from the bottom of the ring, the outer surface of the ring around the periphery of these openings being formed as a collar or boss, as indicated at 20 and the interior of the openings being threaded, as indicated at 21, for the reception of wash-out plugs 22 which are correspondingly threaded at 23 and adapted to be tightly 40 screwed into said openings. By thus providing the wash-out openings at the corners of the ring slanting downwardly from the bottom thereof, as distinguished from the usual practice where the openings are located parallel to the bottom of the ring in the side thereof, an easier out-flow of water is provided. Integrally formed on the bottom of the mud ring are vertical flanges 24 provided with bolt holes 25 for attaching and supporting the boiler, in the usual manner, to the frame of the locomotive.

45 By the foregoing construction it will be seen that there is provided a structure of substantially reduced weight, which is sufficiently sturdy and embodies the character-

istic of flexibility, so as to enable it to adjust itself to irregular expansion and contraction movements of the boiler due to differences and changes in temperature, while at all times maintaining the joints steam-tight and withstanding all stresses imposed upon them by reason of boiler pressure between the sheets, and the shocks and vibrations of the frame structure of the locomotive which are common to everyday practice. The structure is further characterized by its simplicity, easiness of assembly and the relatively low cost.

50 While there has been herein described a specific embodiment of the instant invention it will be understood that many and various changes and modifications may be made thereto without departing from the spirit of the invention, and that all and any such changes and modifications as fall within the scope of the appended claim are contemplated as a part of the present invention.

55 The invention claimed and desired to be secured by Letters Patent is:

60 In a locomotive boiler, the combination of a mud ring comprising integrally formed U-shaped members extending along opposite sides of the boiler fire box, each member having a base and two spaced walls united with and extending upwardly from the base providing therewith a channel open at the top, said spaced walls each having a longitudinal row of spaced threaded orifices near its upper edge, the orifices on one side being aligned with the orifices on the opposite side providing pairs, and said members having thickened portions on each side beginning at a point between the row of orifices and the bottom of said channel and extending below the bottom of said channel, to reinforce the union between said base and said walls, each of said thickened portions forming a shoulder with the adjacent upwardly extending portion of the wall; a boiler plate adjacent the exterior face of each of said upwardly extending portions and having perforations registering with said threaded orifices and having a lower edge spaced above the adjacent shoulder, said edge being welded to said shoulder to form an integral jointure between the plate and adjacent thickened portion; and a row of bolts each extending across the channel and having its respective ends threaded through the orifices of one of said pairs, extending through the perforations of the adjacent plates and headed over at its outer ends, whereby said extensions are rigidly held in fixed, spaced relation and said sheets are held snugly against said extensions.
